A. HENDERSON

CONCRETE POLE

Filed Aug. 23, 1922

UNITED STATES PATENT OFFICE.

ALBERT HENDERSON, OF PITTSBURGH, PENNSYLVANIA, ASSIGNOR TO HENDERSON CORPORATION, OF PITTSBURGH, PENNSYLVANIA, A CORPORATION OF PENNSYLVANIA.

CONCRETE POLE.

Application filed August 23, 1922. Serial No. 583,806.

To all whom it may concern:

Be it known that I, ALBERT HENDERSON, a citizen of the United States, residing at Pittsburgh, in the county of Allegheny and 5 State of Pennsylvania, have invented certain new and useful Improvements in Concrete Poles, of which the following is a specification.

This invention relates to reinforced concrete construction and has special reference to the production of poles and piles, the invention relating particularly to the manner of combining pre-cast reinforced concrete blocks to produce a pole, such as a telegraph 15 or trolley pole or a pile, and connecting the blocks so as to produce a strong permanent structure. The invention is illustrated in the accompanying drawings and will be hereinafter fully set forth.

20 In the drawings—

Figure 1 is an elevation of a trolley pole embodying my invention;

Figure 2 is a detail perspective view of 25 one of the blocks employed in the pole shown in Figure 1;

Figure 3 is an end view of the same block illustrating one means for reinforcing the block and tying it in the completed structure;

30 Figure 4 is a detail elevation showing another form of pole embodying the invention;

In producing a pole in accordance with my present invention, a suitable foundation 35 hole is dug at the site selected for the pole, and blocks 1 are superposed one upon another from the bottom of the hole to a point corresponding to the top of the pole. The lowermost block may rest upon an anchor 40 2 which may be of concrete or may be of metal suitably coated to prevent corrosion. The blocks are constructed with a plurality of openings 3 therethrough to permit the insertion of reinforcing and tying rods, indicated at 4, through the entire series of 45 blocks and it will be understood, of course, that, when the blocks are molded or manufactured at the central plant, suitable reinforcements will be embedded therein, which 50 reinforcements may be of any convenient or preferred form. In opposite ends or faces of the blocks, grooves 5 are formed to accommodate tying reinforcing members, such as shown at 6, whereby to facilitate the connecting of cross arms and braces to the main

body of the pole. The reinforcing rods, indicated at 4, may be metallic bars equal in length to the height of the pole and anchored in any convenient or preferred manner to the foot or base 2 and at the top of 60 the pole. These bars will be placed under tension in any convenient or preferred manner so as to securely clamp all the blocks together and, if desired, the joints between the blocks may be pointed up with grout or 65 other plastic filling so that, when said filling or binding has set, a monolithic structure will be had. In Figure 1, I have shown the pole provided with a lateral arm 7 and a strut or brace 8 extending between the bottom of said arm and the side of the pole. This arm and the brace are likewise constructed of reinforced concrete blocks held together by a tying reinforcement 9, the ends of which are carried into the joints between 70 adjacent blocks of the pole and the arm respectively, as indicated at 10 and as shown more in detail at 6 in Figure 3. After the blocks are in place, grout is poured through the openings 3 so as to bind the entire mass 75 together and embed the tying reinforcing rods, and to accomplish this same result in the arm and the brace and also to accommodate the tying reinforcement 6 or 10, the blocks may be chipped or cut, as indicated at 80 11, to accommodate said reinforcements and permit the introduction of the plastic binder into the joints, it being understood that this binder or filler will flow through all the grooves 5 and, when set, will constitute a 85 key holding the blocks together in a monolithic structure.

To facilitate the work of linemen, steps 12 are provided and these steps may be merely rods having their ends upturned, 90 the length of the rods being greater than the width of the pole so that, if the rods be fitted in the central groove 5 between adjacent blocks, the ends thereof will project beyond the sides of the pole and constitute 95 steps to receive the feet of the workmen in an obvious manner.

In Figure 4 I have shown a tapered block 19 interposed in the pole so that at one or more points in the height of the pole the diameter of the same may be decreased, thereby reducing the weight of the pole units as it reaches a greater height. In Figure 4, furthermore, I have shown a guy wire or trolley-supporting wire 20 carried by the 100 105 110

upper end of the pole, the wire being engaged in a hook or eye 21 tied into the joint between two adjacent blocks, as will be readily understood.

5 I claim:

1. A pole formed of superposed blocks tied together by reinforcing rods extending therethrough, and an arm connected to the pole and formed of blocks arranged end to end and tied together by reinforcing rods extending therethrough and connected to certain of said first-mentioned rods, substantially as described. 70
  2. A pole formed of superposed blocks tied together by reinforcing rods extending therethrough, and an arm extending from the pole and formed of blocks arranged end to end and tied together by reinforcing rods extending therethrough, said last-mentioned reinforcing rods extending into the pole and being connected to certain of said first-mentioned rods, substantially as described. 75
  3. A pole formed of superposed pre-cast cementitious blocks tied together by reinforcing rods extending therethrough, and an arm extending from the pole and formed of pre-cast cementitious blocks tied together by reinforcing rods extending therethrough, said last-mentioned reinforcing rods extending between meeting end faces of certain of the blocks of the pole and being connected to certain of said first-mentioned rods, substantially as described. 80
  4. A pole formed of superposed pre-cast cementitious blocks having grooves in their end faces filled with grout, metal rods embedded in said pole and tying the blocks thereof together, an arm extending from the pole and formed of pre-cast cementitious blocks arranged end to end, and metal rods embedded in the arm and extending into the grooves between meeting end faces of certain of the blocks of the pole and tying the arm thereto, substantially as described. 85
  5. A pole formed of superposed pre-cast cementitious blocks having grooves in their end faces filled with grout, metal rods embedded in said pole and tying the blocks thereof together, an arm extending from the pole and formed of pre-cast cementitious blocks arranged end to end, and metal rods embedded in the arm and having a looped portion positioned in the grooves between meeting end faces of certain of the blocks of the pole and tying the arm thereto, substantially as described. 90
  6. A pole formed of superposed pre-cast cementitious blocks tied together by reinforcing rods extending therethrough, an arm connected to the pole and formed of precast cementitious blocks arranged end to end and tied together by reinforcing rods extending therethrough and connected to certain of said first-mentioned rods, substantially as described. 95
- strut connected at its ends to said pole and arm and formed of pre-cast cementitious blocks arranged end to end and tied together by reinforcing rods extending therethrough and connected to certain of the rods of the pole and the arm, substantially as described.
7. A pole formed of superposed pre-cast cementitious blocks tied together by reinforcing means extending therethrough, an arm extending from said pole and formed of pre-cast cementitious blocks arranged end to end and tied together by reinforcing means extending therethrough and between meeting end faces of certain of the blocks of the pole to tie the arm thereto, and a strut extending diagonally between said pole and arm and formed of pre-cast cementitious blocks arranged end to end and tied together by reinforcing means extending therethrough and between meeting end faces of certain of the blocks of the pole and of certain of the blocks of the arm to tie the strut to the pole and arm, substantially as described. 100
8. A pole formed of superposed precast cementitious blocks, a portion of the pole being formed of blocks of the same dimensions and each in the form of a right parallelepipedon and another portion of the pole being formed of similar blocks of the same size but having a different cross sectional area than the blocks of the first portion of the pole, and continuous reinforcing rods extending through all of said blocks and tying them together, substantially as described. 105
9. A pole formed of superposed pre-cast cementitious blocks, a portion of the pole being formed of blocks of the same dimensions and each in the form of a right parallelepipedon and another portion of the pole being formed of similar blocks of the same size but having a different cross sectional area than the blocks of the first portion of the pole, a reducer block interposed between said portions of the pole and having its end faces of the same cross sectional areas as the blocks in contact therewith, and continuous reinforcing rods extending through all of said blocks, including said reducer block, and tying them together, substantially as described. 110
10. A pole formed of superposed blocks having registering grooves in their meeting end faces filled with grout, said blocks being tie together by reinforcing rods extending therethrough, and an arm extending from the pole and formed of blocks arranged end to end and tied together by reinforcing rods extending therethrough and connected to certain of said first-mentioned rods, substantially as described. 115
- In testimony whereof I affix my signature.

ALBERT HENDERSON. [L.S.]
